David C. Peterson, Chicago, Ill., assignor to
Stewart-Warner Corporation, Chicago, Ill., a
corporation of Virginia

Application July 8, 1948, Serial No. 147,436

Term of patent 14 years

(Cl. D52—2)

To all whom it may concern:

Be it known that I, David C. Peterson, a citizen of the United States, residing at 60 East Scott Street, Chicago, in the county of Cook and State of Illinois, have invented a new, original, and ornamental Design for a Combined Gasoline and Oil Dispensing Island Cabinet, of which the following is a specification, reference being had to the accompanying drawings, forming part thereof.

Fig. 1 is a perspective view of the combined gasoline and oil dispensing island cabinet, showing my new design;

Fig. 2 is a plan view thereof; and

Fig. 3 is an end elevational view thereof.

I claim:

The ornamental design for a combined gasoline

and oil dispensing island cabinet, substantially as shown.

DAVID C. PETERSON.
